(57) **CLAIM**

The ornamental design for a rechargeable dispenser, as shown.

DESCRIPTION

FIG. 1 is a front exploded perspective view of a rechargeable dispenser showing our new design;

FIG. 2 is a rear elevation view thereof;

FIG. 3 is a front elevation view thereof;

FIG. 4 is a right side elevation view thereof;

FIG. 5 is an alternative rear elevation view thereof;

FIG. 6 is a top plan view thereof;

FIG. 7 is a bottom plan view thereof;

FIG. 8 is a front perspective view thereof;

FIG. 9 is a front perspective view of the inner portion of the dispenser;

FIG. 10 is a top plan view thereof;

FIG. 11 is a bottom plan view thereof;

FIG. 12 is a rear elevation view thereof;

FIG. 13 is a left side elevation view thereof;

FIG. 14 is a front side elevation view thereof; and,

FIG. 15 is a right side elevation view thereof.

The broken line showing of environment in the drawings is included for the purpose of illustrating only and forms no part of the claimed design.
